(57) **CLAIM**

The ornamental design for an ergonomic cold roller, as shown and described.

DESCRIPTION

FIG. 1 is a perspective view thereof;

FIG. 2 is a top view thereof;

FIG. 3 is a bottom view thereof; and,

FIG. 4 is a side view thereof, the opposite side being a mirror image thereof.

The features of the ergonomic cold roller are shown and described in the drawings. The broken lines as shown in FIGS. 2-3 are shown for illustrative purposes only and form no part of the claimed design.

1 Claim, 4 Drawing Sheets
